UNITED STATES PATENT OFFICE.

JAMES H. RAND AND JAMES H. RAND, JR., OF NORTH TONAWANDA, NEW YORK.

FILING DEVICE.

1,158,074.

Specification of Letters Patent. Patented Oct. 26, 1915.

Application filed April 29, 1914. Serial No. 835,087.

To all whom it may concern:

Be it known that we, JAMES H. RAND and JAMES H. RAND, Jr., citizens of the United States, and residents of North Tonawanda, in the county of Niagara and State of New York, have invented new and useful Improvements in Filing Devices, of which the following is a specification.

This invention relates to filing devices, and particularly to filing devices of the kind having a base and spindles on which tickets containing various entries or memoranda, bills, and other papers are temporarily filed.

The objects of the invention are to provide means whereby the upright spindles may be bent or swung back into recumbent position upon the desk or table, and into open relation to the base, to enable the user to lay open the package of papers on the spindles, and turn the sheets freely, after the manner of the leaves of a book; and otherwise to improve the construction, and render more convenient the operation of such filing devices; all as hereinafter described and particularly pointed out in the claims.

In the accompanying drawings which illustrate certain embodiments of the invention,—Figure 1 is a longitudinal section, partly in side elevation of a filing device containing the invention; Fig. 2 is a plan view of said filing device; Fig. 3 is a side view, partly in section showing the spindles bent back into recumbent position; Fig. 4 is a plan view of another form of filing device containing the invention; Fig. 5 is a section on line 5—5 of Fig. 4; Fig. 6 is a section on line 6—6 of Fig. 4; and Fig. 7 is a partial side view of the form of filing device shown in Fig. 4.

Referring first to Figs. 1 to 3, A represents the base, which may be a wooden board, and A' a swinging section hinged to the board A by a hinge or butt a. The hinged section A' in this form of the invention preferably consists of a metal plate. C, C, represent a pair of filing spindles, and preferably consists of the two legs of a U-shaped rod of wire, which extend upward through two holes provided therefor in plate A', with the cross part c, which connects the two legs, extending between the two holes on the under side of the plate, and there secured to the plate by solder or other suitable means. Said cross part c is housed in a slot a' formed in the base A and extending between

the holes through which spindles C, C, project. When the spindles are in upstanding or normal position as shown in Figs. 1 and 2, they are locked in that position by a yielding, spring actuated lock, consisting of the headed bolt B extending through a bore in the end of the base, and provided with a hook b which engages the edge of the plate A' and holds the plate A' and the spindles 65 against movement on the base. Said lock is normally urged into locking position by springs s, but may be unlocked to release the plate A' by merely pressing the bolt B inward. The sheets are filed on the spindles 70 in the usual way and form a package D of greater or less thickness according to their number. If the user wishes to inspect the sheets of package D, he unlocks the hinged section or plate A' and swings the spindles 75 from their upstanding position shown in Fig. 1, to their open or recumbent position as shown in Fig. 3, so that both the base and the spindles lie out on the table or desk and enable the user to turn the sheets and to lay 80 them flat in either direction without interference by the spindles or the base, where they may be conveniently inspected precisely like the leaves of a book.

In the form of the invention shown in Figs. 4 to 7 the base is divided into two sections, the main section A and the swinging section A², corresponding to the hinged plate A' of the other form, hinged to the main section by hinges or butts a. The legs of the U-shaped rod, constituting spindles C, C, extend upward through a pair of holes provided therefor in hinged section A², and the cross part c of the U-shaped rod is housed in a slot a² formed in the under side of the section A² and extending between said holes. Said spindles are removably secured in place by a pin e, which extends from the inside or abutting surface of the hinged section A² across the slot a², below the cross part c, to hold the latter in place. The pin e is made with a head or hook e' which may be used for withdrawing the pin, and the abutting surface of the section A is countersunk to receive the head so that it will not interfere with the closing of the base. When the base is in normal position the head of pin e is covered, and the pin prevented from becoming accidentally dislodged. A spring lock is provided to hold the base sections in normal position, consisting of the resilient plate f, secured to one of the hinged members, hav-

ing a hole g , which snaps over and engages a stud h on the other member. The hinged section A^2 is shown in folded condition and the spindles C in recumbent position, in 5 broken lines in Fig. 7. The operation of the device for the inspection of the sheets D is the same as already described with reference to the form shown in Figs. 1 to 3.

In order to prevent the accidental dislodgment of the sheets D from the spindles, there may be provided a sheet-holder in the 10 form of a yoke K , the ends of which are curved to engage the spindle C, C , as shown at h' . A tension spring k^2 connects the yoke K with the base, and yieldingly holds the yoke down upon the package of the sheets D . The yoke is removable from the spindles by merely stretching spring k^2 and disengaging the ends h' from the spindles, to 15 permit sheets to be placed upon or removed from the spindles. It will be clear that the yoke makes sliding engagement with the spindles and is adjustable up and down thereon to accommodate packages D of varying thickness. Although we have shown the sheet-holding yoke only in Figs. 4 and 5, it 20 will be understood that it is equally applicable to the form of the invention shown in Figs. 1 to 3.

30 The U-shaped rod, with its legs projecting upward through holes in one of the base sections, and its cross part extending underneath the base section and housed in a slot, affords a very rigid and secure pair of spindles; much less likely to work loose from the 35 base than separate spindles set into the base in the usual way, and impossible to pull out in use or even by rough handling.

We claim:

40 1. A filing device comprising a base having a pair of holes opening through its top surface, and a U-shaped rod, the legs of

which constitute a pair of filing spindles extending upward through said holes, said base also having a slot extending between said 45 holes, in which the cross part which connects the legs of said U-shaped rod is housed.

2. A filing device comprising a base divided into a main section and a hinged section, said hinged section having a pair of 50 holes therethrough and a slot connecting said holes on the under side, a U-shaped rod, the legs of which constitute a pair of filing spindles extending upward through said holes, and the cross part of which is housed 55 in said slot, and a pin extending from the inside or abutting surface of said hinged section across said slot to hold the cross part of said U-shaped rod in position.

3. A filing device comprising a base having a pair of holes therethrough and a slot connecting said holes on the under side, a U-shaped rod, the legs of which constitute a pair of filing spindles extending upward through said holes, and the cross part of 65 which is housed in said slot, and a pin extending across said slot to hold the cross part of said U-shaped rod in position.

4. A filing device comprising a base, filing spindles extending upward from the base, a 70 sheet holder consisting of a yoke extending between the spindles, the ends of the yoke removably engaging the spindles at one side only, and a spring connecting said base and yoke yieldingly pressing the latter against 75 the spindles and down upon the sheets.

Signed at North Tonawanda, New York, this 24th day of April 1914.
